UNITED STATES PATENT OFFICE

MICHAEL EVEN, OF PORT WASHINGTON, WISCONSIN.

TLTING-CHAIR.

SPECIFICATION forming part of Letters Patent No. 638,224, dated December 5, 1899.

Original application filed July 5, 1899, Serial No. 722,809. Divided and this application filed October 11, 1899. Serial No. 733,275. (No model.)

To all whom it may concern:

Be it known that I, MICHAEL EVEN, a citizen of the United States, residing at Port Washington, in the county of Ozaukee and 5 State of Wisconsin, have invented certain new and useful Improvements in Tilting-Chairs, of which the following is a specification, reference being had to the accompanying drawings, forming a part thereof.

10 This application is a division of application Serial No. 722,809, filed July 5, 1899.

The main object of my invention is to improve the construction and operation of devices of this class.

15 It consists in certain novel features in the construction and arrangement of parts, as hereinafter particularly described, and pointed out in the claims.

20 In the accompanying drawings like letters designate the same parts in the several figures.

Figure 1 is a vertical longitudinal section on the line 1 1, Fig. 2, of tilting-chair irons embodying my improvements. Fig. 2 is a 25 horizontal section on the line 2 2, Fig. 2; and Fig. 3 is a vertical longitudinal section on the line 3 3, Fig. 1.

A is a head mounted on the upper end of the revolving spindle B or otherwise connected 30 with a chair-base. (Not shown.) It is formed or provided with upturned arms a a.

C is a spider or frame to which the chair-seat (not shown) is attached in the usual or any suitable way. It is formed or provided 35 with depending ears c c, which are fitted over and are pivotally connected with the arms a a near their lower ends by a bolt or pin D, passing horizontally through them crosswise of said spider or frame A.

40 E is a bolt loosely engaging at its head with a depending forked or slotted arm c' on the under side of the spider C and extending horizontally forward therefrom above and transversely to the pivot pin or bolt D. It is 45 threaded at its front end and provided with a nut e.

F F are spiral springs arranged on opposite sides of and parallel with the bolt E between perforated bearing-plates G G', against which 50 said springs are seated at their ends and

through which the bolt E loosely passes. The nut e bears against the outer or front plate G, and the inner or back plate G' is provided at its ends with pivots g g, which have seats or bearings on the arms a a of the head A. 55 These pivots g g are preferably offset, so that when the spider C is tilted with the chair-seat the spring-seats on the front face of the plate G', with the rear ends of the springs F F, will move up and down as said plate rocks upon its pivot-bearings in conformity with the up-and-down movement of the bolt E produced by the tilting of the chair-seat and spider C. Strains which tend to break, twist, or bend said bolt or springs are thus avoided, and the 60 parts are caused to work freely without binding when the spider is tilted backward and forward. The pivots g g may be located, as shown in the drawings, to the rear of the spring-seats on the plate G', or they may be 65 placed in advance of said seats. In either case the spring-seats will move up and down with the bolt E and keep the springs F approximately parallel with said bolt, as above explained. 70

The arms a a project upwardly underneath and close to overhanging flanges or parts of the spider C and are extended at their upper ends horizontally from front to rear, so that by engagement with the spider they will serve 75 as positive stops for limiting its tilting movement both backward and forward.

When the chair-seat, with the spider C, is tilted backward, the arm c' will be moved rearwardly away from the plate G', thereby 80 drawing the bolt E endwise through said plate, which is held by the head A in a relatively stationary position. This endwise movement of the bolt, which carries the front plate G backward with it, compresses the 85 springs F F, which offer a gradually-increasing resistance to the backward movement of the chair-seat. The tension of said springs is adjusted as desired by means of the nut e. The overhanging flanges or parts of the spider 90 C, engaging with the front and rear corners of the arms a a, limit the backward and forward movement of the chair-seat at the desired points. 95

Various modifications in the minor details 100

of construction may be made without departing from the principles and intended scope of my invention.

I claim—

5 1. The combination with a head having up-turned arms, of a frame having depending ears pivoted to said head and provided between said ears with a downwardly-projecting arm, a bolt engaged at one end with said arm
10 and provided at the opposite end with a nut, two perforated plates through which said bolt passes, one of said plates being pivotally supported against the arms of said head and the other bearing against said nut, and a spring
15 interposed between said plates, substantially as and for the purposes set forth.

2. The combination with a head having up-turned arms, of a frame having depending ears pivoted to said arms and provided between said ears with a downwardly-projecting arm, a bolt engaged at one end with said arm and provided at the other end with a nut, two perforated bearing-plates, through which said bolt passes, having spring-seats on their

opposing faces, one of said plates having offset pivots bearing against the arms on said head, and spiral springs interposed between and bearing at their ends against said plates on opposite sides of and approximately parallel with said bolt, substantially as and for the purposes set forth.

3. The combination with a head having up-turned arms, of a frame having depending ears pivoted to said arms which are horizontally extended at their upper ends underneath overhanging portions of said frame and constitute therewith stops for limiting the tilting movement of said frame, and a spring opposing the backward movement of said frame, substantially as and for the purposes set forth.

In witness whereof I hereto affix my signature in presence of two witnesses.

MICHAEL EVEN.
